ATTORNEY.

UNITED STATES PATENT OFFICE.

FELIX MANIER, OF PIQUA, OHIO.

COMBINED NUT AND PIPE WRENCH.

1,076,133.

Specification of Letters Patent. Patented Oct. 21, 1913.

Application filed March 24, 1913. Serial No. 756,549.

To all whom it may concern:

Be it known that I, FELIX MANIER, a citizen of the United States, and residing at No. 529 West High street, in Piqua, in the county of Miami and State of Ohio, have invented certain new and useful Improvements in a Combined Nut and Pipe Wrench, of which the following is a specification.

My invention pertains to that class of sliding-jaw wrenches wherein each jaw and a handle form a one piece part, and by which one piece parts the wrench is adjusted.

My invention has for its object, to provide a non-sticking wrench with great leverage, which is simple in construction, positive in action and admits of quick adjustment.

Other objects and advantages will be apparent from the following description.

In the drawings, Figure 1 is a sectional view along the line $x-y$ of Fig. 2. Fig. 2 is a side elevation with parts broken away showing the position of the dog C and the spring G and Fig. 3 is a side elevation with the jaws separated and the handles spread.

Referring to the drawings wherein like characters represent the same parts throughout, A represents the outer jaw with the shank and handle A', and with a transverse opening A³ through the shank part thereof, and in which transverse opening the dog C is operated. Said upper jaw A has a serrated surface F attached thereto by means of the screw b.

B represents the inner jaw with the handle, with a longitudinal opening therein and therethrough, and through which longitudinal opening said handle and shank part A' of the jaw A passes. Said lower jaw B is provided with the serrated surface F' attached thereto by means of the screw b'. Said jaw B has pivoted thereto at E in said longitudinal opening and fitting in said transverse opening A³ of the shank part A' of the jaw A, a dog C. Said dog C is provided with the teeth C' which teeth C' are forced in mesh with the teeth A² extending into said transverse opening A³ from the shank part A' of the jaw A by means of the spring G. Said spring G is attached to said dog C at I. Said dog C is also provided with a pin D, which pin D extends therefrom out through the opening D' in the wall of the jaw B. By means of said pin D when the handles A' and B are spread the teeth

C' are released from in mesh with the teeth A² and either the jaw A or the jaw B may be operated out or in at the will of the operator to adjust the wrench to the size of the nut or pipe to be operated upon. The jaw B is cut away at H in order to permit of the spreading of the handles A' and B as indicated in the Fig. 6 of the drawings.

It will be readily noticed that in the wrench described the fulcrum point is at all times from under any part of the nut or pipe being operated upon and by reason thereof the wrench is rendered non-locking. By non-locking is meant a wrench that is readily and easily released from engagement in operating upon a nut or pipe. The wrench described will operate upon and can be released from operation on, readily and quickly, any sized nut or pipe. It will be further noticed that the same amount of leverage is obtainable on large nuts or pipes as on small ones. This same degree of leverage is obtained by reason of the handle B acting as a lever the lower end thereof being at all times the same distance from the point of fulcrum. This is not true in other wrenches. In other wrenches the larger the nut or pipe the less the leverage. It will also be noticed that the more power is applied to the lever handle B the more firmly the nut or pipe operated upon is held.

Having fully described my invention so that others skilled in the art can make the same, what I claim and desire to secure, by Letters Patent, is:—

In a pipe wrench the combination of a stationary member comprising a jaw portion having serrations, and a handle portion provided with a longitudinal slot having teeth along one edge of said slot; a movable member provided with a transverse slot, having a jaw portion provided with serrations coacting with said first-named serrations, a handle portion and a pivot portion; a pin passing through said slot and pivot portion causing the serrations of the movable member to swing angularly with respect to the serrations of the stationary member when said movable member is swung on said pin, and causing the serrations of the movable member to move bodily to and from the serrations of the stationary member when the pin of said movable member is moved up and down in said slot; a pawl having teeth adapted to engage said first-named teeth,

pivoted on said pin, and adapted to swing independently of said movable member; a pin passing through said pawl and said transverse slot in the said movable member; 5 and a spring controlling said pawl located in said transverse slot, substantially as described.

In testimony whereof I hereto affix my signature in presence of two witnesses.

FELIX MANIER.
